UNITED STATES PATENT OFFICE.

EMIL R. DRAVER, OF RICHMOND, INDIANA.

WHEEL-CARRIER.

1,322,678

Specification of Letters Patent. Patented Nov. 25, 1919.

Application filed November 19, 1917. Serial No. 202,716.

To all whom it may concern:

Be it known that I, EMIL R. DRAVER, a citizen of the United States, residing at Richmond, in the county of Wayne and State of Indiana, have invented certain new and useful Improvements in Wheel-Carriers; and I do hereby declare the following to be a full, clear, and exact description of the invention, such as will enable others skilled in the art to which it appertains to make and use the same.

My present invention has for its object to provide an improved wheel carrier for automobiles which is adapted to carry one or more extra wheels, the term "wheel" being herein used in a broad and liberal sense.

The invention involves an extensible spindle and coöperating devices whereby one or more such wheels may be carried. For carrying one wheel, one section, to wit, the main or relatively fixed section of the spindle is used, and for carrying a second extra wheel, the detachable spindle section is applied to the main section. The outer ends of the main and of the supplemental or extension section of the spindle are preferably provided with duplicate threads so that a single clamping device may be applied to either thereof. Also, as the best means for detachably connecting the supplemental spindle section to the main section, the former is provided with an internally threaded seat adapting it to be screwed onto the threaded end of the main spindle.

Preferably, the spindle is adapted for carrying one or more wire wheels such as commonly used on automobiles. However, by the provision of a sort of skeleton hub and spoke structure, demountable rims may be carried on the spindle much in the same manner as the ordinary wire wheels.

In the accompanying drawings which illustrate the invention, like characters indicate like parts throughout the several views.

Referring to the drawings,

Figure 1 is a view, chiefly in vertical section, but with some parts shown in dotted lines illustrating my improved wheel carrier applied to the rear of an automobile;

Fig. 2 is a perspective view showing the main section of the spindle;

Fig. 3 is a perspective view showing the extension or supplemental section of the spindle;

Fig. 4 is a perspective view of a sleeve-like so-called spacing washer;

Fig. 5 is a perspective view showing a modified form of spacing washer;

Fig. 6 is a plan view showing a modified form of wheel clamping cap;

Fig. 7 is an elevation showing a temporary hub and spoke structure for supporting a demountable rim from the spindle; and

Fig. 8 is a section on the line 8—8 of Fig. 7.

The numeral 9 indicates a bracket that is rigidly secured to the rear portion of an automobile frame, the same as shown, being connected to the frame 10 of the automobile by a brace bar 11 and a cross rod 12, which latter extends between and is secured to the rearwardly projected portions of the side bars of said frame 10. The main spindle or fixed section of the multi-section spindle is preferably constructed, as shown in Figs. 1 and 2, and, as shown, it comprises a spindle proper 13, having a hub 14 with a radial hub 15 engaging flanges 16. The spindle 13 is shown as passed through and rigidly secured to the upper end of the bracket 9 and its projecting end is threaded at 13^a.

The supplemental or extension spindle 17 has an internally threaded socket 18 and radially projecting longitudinal hub engaging flanges 19. The threads of the socket 18 fit the threads 13^a of the main spindle 13, so that the supplemental section is adapted by this means to be screwed onto the said main spindle. To firmly lock the supplemental spindle to the main spindle, it is shown as provided with a set screw 20 applied through its socket 18. The projecting end of the supplemental spindle 17 has threads 17^a that correspond to the threads 13^a of the main spindle.

A suitable spacing washer, so-called, is preferably telescoped onto the flanges 19 of the supplemental spindle for engagement with the hubs of the wheels carried by the spindle. In the form illustrated in Figs. 1 and 4, the spacing washer is in the nature of a sleeve 21, the end flanges of which are notched at 22 and are adapted to be slid onto the flanges 19. At its inner end, the sleeve 21 has a relatively small conical surface 23; and at its outer end, it has a relatively large reversely beveled conical portion 24 for a purpose which will presently appear.

The numeral 25 indicates a clamping nut which, as shown, is provided with a projecting arm 26 by which it may be readily rotated. This clamping nut 25 is adapted

to be screwed at will, either onto the threaded end 17^a of the segmental spindle or onto the threaded end 13^a of the main spindle. Loosely placed on the extension spindle 17, or on the main spindle 13, according to whether one or two wheels are carried, is a so-called clamping head 27 which has radially and inwardly projecting flanges 28.

10 In Fig. 1, two wire wheels of standard construction are illustrated, and of the parts thereof, *a* indicates the rim, *b* the hubs, *c* the spokes, and *d* the tires. In the use of the carrier to carry two wheels, as shown in Fig. 1, the flanges 16 of the main spindle engage the adjacent flaring inner surfaces of the hub of the inner wheel and the stop flange 15 limits the inward movement of the wheel on the spindle. The small conical end 23 of the spacing washer 21 engages the flaring inner surface of the outer end portion of the hub of the said inner wheel and the beveled end 24 of said washer engages the flaring inner surface of the inner end 25 of the hub of the second or outer wheel. The flanges 28 of the clamp 27 engage the flaring inner surface of the outer end of the hub of the second or outermost wheel. With this arrangement, when the nut 25 is applied to and tightened, the so-called spacing washer will shift and adapt itself to the two wheels and the hubs of the two wheels will be firmly clamped by the engaging elements of the spindle. Thus, the wheels will be securely held against rattling on the spindle and, moreover, the hubs and other parts of the two wheels will be held out of direct contact.

Fig. 5 illustrates a simple modified form 40 of the spacing washer which is adapted to be substituted for the more complex form shown in Figs. 1 and 4. Fig. 6 illustrates a modified form of clamping nut and clamping head wherein the two are formed as one element and in which the numeral 30 indicates a cylindrical head having an internally threaded hub 31 and a beveled or conical inner end 32. The hub 31 is adapted to be screwed onto the threaded end 17^a of the extension spindle or onto the threaded end 13^a of the main spindle, at will. The body of the head 30 is of a size and approximately fits the outer end of the hub in which it is applied and its beveled end surface 32 will engage with the inner outwardly flaring surface of the outer end of the wheel.

When but one wheel is to be carried, the extension spindle 17 and spacing washer are removed and the clamping head and clamping nut will then be applied to the threaded end of the main spindle. This extensible spindle is, therefore, easily readjusted to adapt it to carry either one or two wheels. An automobile may be sold

with the equipment for holding but one 65 wheel and thereafter the additional elements may be purchased and applied, thereby converting the spindle into one that is adapted to carry two wheels. Of course, more than two wheels might be carried on a single 70 extensible spindle, but it is not believed to be desirable to carry more than two extra wheels. However, the number of spindle sections employed will simply depend on the 75 number of wheels that are to be carried.

When demountable rims are to be carried on the spindle, a sort of temporary hub and spoke structure will be provided as a connection between the spindle and the demountable rim. In Figs. 7 and 8, such a 80 hub and spoke structure is provided, the same as shown, comprising a hub 33 having one or more, to wit, as shown, three radial spokes 34 which, at their outer ends, have transversely extended head portions 35 onto 85 which the demountable rim 36 is adapted to be telescoped. The rim 36 is shown as provided with a tire 37. Either one or two of the hub and spoke structures 33, 34, and 35 may be applied to the spindle and secured in any suitable way and any suitable means may be provided for securing the demountable rims to the respective heads 35.

In Fig. 1, the numeral 10^a indicates the 90 gasolene tank, 10^b the rear springs and 10^c the body of the automobile.

The term "spindle" is herein used in a broad and liberal sense to include any sort of structure that will pass through the hubs of one or more wheels and serve to support 100 the same.

What I claim is:

An extra wheel carrier for vehicles, comprising a main spindle section having means for rigidly securing it to the vehicle and 105 having a wheel stop on its inner portion, and which main spindle is adapted to carry an extra wheel, a supplemental spindle detachably secured to the end of said main spindle and adapted to carry a second extra 110 wheel, a wheel clamping device applicable to the end of said main spindle or to the end of said supplemental spindle, according to whether one or two extra wheels are to be carried, and a wheel spacing device 115 mounted to slide freely on the intermediate portion of the complete spindle in the vicinity of the joint between said main and supplemental spindle sections, and which spacing device is freely removable from the complete spindle without separating the two 120 spindle sections.

In testimony whereof I affix my signature in presence of two witnesses.

EMIL R. DRAVER.
